UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

CARBURETOR.

Application filed April 30, 1919. Serial No. 283,790.

To all whom it may concern:

Be it known that I, LIONEL M. WOOLSON, a citizen of the United States, and resident of Detroit, Wayne County, State of Michigan, have invented certain new and useful Improvements in Carburetors, of which the following is a specification.

This invention relates to carburetors for hydrocarbon motors and more particularly to carburetors of the down draft type. One of the objects of the present invention is to provide a carburetor of improved form, which is more simple in its construction, more easily manufactured, and the various parts of which are more accessible.

With the above and other objects in view, the invention is embodied in preferable form in the construction and arrangement hereinafter described and illustrated in the accompanying drawings, in which drawings:

Fig. 1 is a top plan view of the carburetor, parts being broken away and shown in section.

Fig. 2 is a vertical section on the line 2—2 of Fig. 1, looking in the direction of the arrows said section being taken through the main or suction jet and through the venturis,

Fig. 3 is a vertical section on the line 3—3 of Fig. 1, looking in the direction of the arrows the same being taken through the compensator well, the idling tube and the connecting passageway of the latter leading to the throttle valve chamber,

Fig. 4 is a section taken on the line 4—4 of Fig. 1,

Fig. 5 is a vertical section taken on the line 5—5 of Fig. 1, and

Fig. 6 is an exterior end view in elevation of the carburetor. Referring to the drawings, the carburetor comprises three principal parts or castings, the main body part or casting A, the air intake part B, and the throttle valve part C. These parts are suitably connected together by screws or bolts and they are so designed that the minimum amount of machine work is required to form the various passages and the cooperating surfaces. In the part A is formed the float chamber and most of the fuel passages, and the mixture forming Venturi tubes are supported by it. The part B forms the main air intake opening, as well as the cover B' for the float chamber. The part C has the throttle valves mounted on it and it forms

the connection between the part A of the carburetor and the intake header or manifold of the engine.

Referring more particularly to the drawings, 10 is a float of usual construction which is mounted in a chamber 11 with which communicates an inlet pipe 12 leading from any suitable source of supply and from which the fuel passes into the chamber 13, having a strainer 14. An inlet bushing 15 leads from the strainer chamber to the float chamber and the opening thereof is controlled by a needle valve 16 operable by the float. An outlet fuel feeding passageway 17 leads from the lower part of the float chamber horizontally through the carburetor body and is adapted to supply the wells from which the gasoline is supplied to the air and fuel mixing and proportioning elements.

The invention is shown as applied to a carburetor of duplex type that is one in which a single source of supply, a single conduit and a single float chamber is shown in connection with a double set of carbureting and proportioning elements and two throttle valves. This arrangement is particularly designed for use in motors of the V type, each half of the duplex carburetor being adapted to supply a proper mixture separately to each set of cylinders. In this construction the two throttle valves are adapted to be operated by connecting mechanism having a common control. In this application since the carbureting elements of each half of the device are identical in construction, the description will be confined to those parts which go to make up one of the complete carburetor units.

The vertical wells which the passageway 17 feeds are indicated by the numbers 18 and 19, the former constituting the main well for supplying fuel under suction, and the latter, having compensating openings communicating with the main well and containing the idling tube for feeding a small supply directly to the throttle valve to drive the motor at idling speed.

The communication with well 18 is through an elongated cross chamber 20, the axis of which is at right angles to the passage 17 and which extends horizontally from the outside surface of a part of the carburetor into the bottom of the vertical well. This chamber has a cylindrical bore and mounted within the same is a screw

plug 21 adapted to hold a plate 22 against a shoulder in the said chamber. This plate is provided with an aperture 23, the area of which determines the quantity of fuel passing to the well 18. A cap plug 24 closes the outer end of the bore of the chamber 20. Beyond said chamber in the line of travel of the fuel the passageway 17 communicates with the well 19 through another cross chamber 25, which has a plug 26, apertured plate or washer 27 and cap plug 28. The use of these removable cap plugs permits the cross chambers to be readily bored from the outer surfaces of the body of the carburetor 15 and provides means of ready access to the plug and apertured plate.

Within the well 18 is a jet tube 29 extending through a screw plug 30, which communicates with the chamber 20. The upper end of the well 18 communicates with a horizontal passageway 31 formed preferably in a horizontally extending tubular member 32, which is fastened by screws to the carburetor body as shown particularly in Figs. 1 and 2. The arm 32 terminates in a head part 33, having the passageway 31 continued therein in the form of an annular recess and communicating with apertures 34 in the wall of a Venturi tube 35 supported by said arm, said apertures 34 being formed in the most contracted portion of said tube. This tube is open to the atmosphere at its upper end and its lower end enters and terminates within an open, outer larger Venturi tube 36. The lower end of the inner tube terminates substantially on a line with the section of greatest contraction of the outer tube whereby a cumulative ejector effect is produced, resulting in obtaining a very high velocity of air in the tube 35. 37 is a throttle valve of the butterfly type located below the end of the tube 36. This throttle valve is mounted in a chamber 38 formed in the body part C of the carburetor. These two body parts A and C are joined together by screw studs 40 and the Venturi tube 36 is clamped between them, as shown particularly in Figs. 2 and 4. This construction enables the parts to be readily assembled and enables the same to be cast without the use of a complicated core.

It will be seen that the point of emergence of the fuel from the passageway 31 into the inner venturi 35 is considerably above the level of the fuel in the float chamber whereby flooding of the carburetor is prevented.

Referring now to the compensating feed from the gravity fed well 19, the latter is open to the atmosphere near its upper end through a passage 41, and an annular space 42 around the contracted part of a valve 53 hereinafter described (see Figs. 3 and 4). The gravity well 19 communicates with the well 18 surrounding the main suction jet 29

by means of compensating holes, or passages 44', which are drilled by means of bores 45 closed by screw plugs 46. These passages are located at different levels and are adapted to be successively uncovered by the fuel to permit the passage of air therethrough as the level of the fuel in the well 18 falls under an increase in suction.

Provision is made for supplying mixture for idling. 44 is a tube, the open lower end

of which extends to near the bottom of the well 19 and receives its fuel therefrom. The tube 44 is fixed to a threaded adjustable head 45 having a conical valve 46 at its lower end which seats against the upper end

of the well 19, the part of the head above the valve being separated from the wall of the well by an annular space 47, the same being cut off from the well 19 when the valve is seated and in communication therewith when the valve is opened. Holes 48

lead through the valve and tube 44. (See Figs. 3 and 5.) These holes and space 47 communicate with a horizontal passageway

49, leading to a vertical passageway 50, which at its lower end communicates with a passageway 51 opening into the throttle chamber 38, at a point opposite the edge of the butterfly valve 37 when the latter is in closed position as shown in Fig. 6. When

the butterfly valve is entirely closed, it seals the outlet of passage 51. When such valve is slightly opened, assuming that the engine is running, a high vacuum results in air blowing past the edge of the valve at very high velocity, thus producing a high suction on passage 51.

This suction is transmitted through passages 50 and 49 to holes 48 in valve 45, as well as to annular space 47. The gravity compensating feed well

19, being full of fuel up to the level maintained by the float, fuel is consequently sucked up the tube 44, through the holes 48 and thence into passage 49. Air is also drawn past the valve seat and space 47 from

the passage 44, which communicates with the atmosphere through passage 41 and annular space 42. The quality of the mixture of air and fuel which is drawn through the

passage 49 is regulated by the valve head 45. If this valve is screwed tight against its seat

so as to close space 47 only fuel will be drawn through the holes 48. If the valve be screwed out considerably the annular

passage 47 at the valve seat will become sufficiently large to satisfy the suction in passage 49, so that only air will be drawn in.

It will thus be seen that an intermediate position of adjustment of the valve head 45 can be readily obtained which will give the

correct rich emulsion to mingle with the air drawn past butterfly valve 37 to form the necessary small amount of explosive mixture to maintain the engine running at

idle speed.

The upper end of the valve head 45 is peripherally serrated and engaged by a spring catch 52 to hold it in adjusted position.

53 is a rotary altitude valve (see Fig. 2) having a port 54 adapted to establish communication between the atmosphere and passage 31, by way of the open annular space 55, hole 56, and passage 57. The function of this valve is to bleed air into the 10 passage 31 when used on an engine operating at high altitudes, so as to relieve somewhat the suction existing in chamber 18 and thus weaken the mixture. The valve has a reduced portion 58 (see Figs. 3 and 15 4) providing the annular air passage space 42 heretofore referred to, and it is operated by a lever 59.

Each of the throttle valves 37 is carried by a shaft 60 and on these shafts are two 20 intermeshing sectors 61, whereby when one of the shafts is turned the other throttle valve will be likewise turned by the gear connection.

In order to prevent an accumulation of 25 liquid fuel in the event of flooding of the float chamber, a drain passageway 63 leading from the upper part of the float chamber to the chamber 55 which surrounds the Venturi, is provided. The wall of this annular chamber is provided with a tapped 30 hole 64 adapted to receive a pipe connection to permit a drain pipe to be attached which pipe may lead outside of the motor and the carrying body.

35 The carburetor is provided with an open chimney 65 extending over both venturis and formed by a body portion B which is detachably secured to the upper part of the main carburetor body by means of screens 66.

40 By the provision of the two separate bodies forming the throttle chamber and the main body a simple structure is provided and one which may be readily cast. The employment of removable plugs 24 and 28, 45 in connection with the provision of the plates 22 and 27 within the chambers closed by said plugs, provides a convenient construction enabling ready access to the plates.

The operation of the carburetor is as follows:—

Assuming that the engine is running idle, the throttle valve 37 is slightly open, and air passes the edge of the throttle valve at high velocity. The valve is so nearly closed, 55 however, that there is very little suction through the Venturi tubes of the carburetor, but there is considerable suction in the passageways 49, 50 and 51. Thus liquid fuel is drawn into the tube 44 from the well 19

60 and air is drawn from the well 19 which is supplied by the passage 41, the proportion of liquid fuel and air being regulated by means of the adjustable valve head 45. This very rich mixture is, of course, diluted to 65 some extent by the air passing the throttle

valve 37, and thus a correct idling mixture is fed to the engine.

As the throttle valve 37 is opened, the main channels for feeding the mixture come into operation because the suction through 70 the Venturi tube 35 is then sufficient to draw the emulsion of fuel through the main passage 31. Until the level in the well 19 falls below the upper port 44', raw liquid will be drawn both from the wells 18 and 19 into 75 the passage 31, but, of course, the upper port 44' is almost immediately uncovered and it then supplies air, which it receives from the port 41, to the well 19, thus forming an emulsion which passes into the passage 80 31 and thence through holes 34 to the Venturi tube 35.

As the throttle valve is opened still farther, thus increasing the suction, the liquid fuel in the well 19 is soon exhausted 85 because the restricted passage in the plate 27 supplies the well by gravity only, or substantially so, due to the atmospheric port 41 at the top of the well. Then all of the ports 44' are uncovered and are supplying air to 90 the well 19. The latter well is under the full suction of the Venturi tube 35, except, of course, for the air fed to it through the ports 44', and an increasing amount of liquid fuel is drawn from the tube 29 for emulsion 95 in the well 18 and the passage 31.

From the above it will be seen that the increasing suction on the well 18 tends to increase the liquid fuel fed to the carburetor, and if this well operated alone, the mixture 100 would be too rich at the higher suctions, but the higher suctions soon drain the well 19 and the latter, therefore, supplies a constantly decreasing amount of liquid fuel relative to air and the net result is a substantially constant proportion of liquid fuel 105 and air formed by the carburetor.

It will be understood further that at the lesser throttle openings the well 19 furnishes a reservoir of fuel for supplying the engine 110 while idling, and it also helps to maintain a rather rich mixture for rapid acceleration.

Also, as has been pointed out hereinabove, air may be bled into the passage 31 through the valve 53, which has been described as an 115 "altitude valve" since its principal use is for operating the carburetor in the higher altitudes where the air is less dense.

Some of the features shown and described in this carburetor are separately illustrated, 120 described and claimed in the co-pending application of Alfred Moorhouse, Serial No. 293,628 to which cross reference is hereby made.

Having thus described my invention, what 125 I claim is:

1. A carburetor comprising a body portion forming a float chamber and a fuel well both open at the top and in the same plane, a mixture pipe connected to said body over 130

the top opening of the well, and an air intake member having a part covering the top of said chamber.

2. A carburetor comprising a body portion having a float chamber and an air passage, an air inlet portion covering the float chamber and having a passage opening into

said air passage, a Venturi tube arranged in said air passage, and a throttle valve portion secured to the body portion and clamp-¹⁰ing the Venturi tube in position.

In testimony whereof I affix my signature.

LIONEL M. WOOLSON.
